COMBINED RAIL TIE PLATE, CLAMP,
AND SLEEVE

Arnold Schroetter, Newark, N. J.

Application February 8, 1946, Serial No. 646,293

9 Claims. (Cl. 238—210)

1

This invention deals with a safety device for rails. More specifically, it relates to a reinforcing unit which may be mounted on a railroad track at weak points in order to prevent accidents.

A survey of a number of railroad accidents has shown that a large proportion of them involve a severance of the rails at a joint. According to present practice, such joints are made up by bolting a steel plate on each side of the narrow section of the rail. The rails are fastened to the ties by spikes fitting through holes in a plate on the tie underneath the rail. These spikes usually cause some splitting of the wood when they are driven in. Then the elements, together with the pounding and the play of the wheels on the rails, begin their erosion and corrosion which, coupled with accelerated decay of the wood around the spikes, soon weaken the hold on the rails and, since the weakest metal section is the joint carrying the plates and rusted bolts, the break at that point is inevitable. This type of structure is particularly unsafe with the advent of heavier cars and engines and road speeds approaching 100 miles per hour.

An object of the present invention is to provide a sleeve for the rails, preferably at the joints, to counteract the bending stress caused by sudden impact upon the rails at those points. Another object is to provide clamps which may be adequately anchored to the ties and which can be made to grip the rail base tightly so as to resist any lifting action caused by sudden impact. Further objects will become apparent from the description.

The invention may be more clearly understood from the drawings in which Figure 1 is an end view of a portion of the rail bed taken perpendicularly to the axis of the rail. Figure 2 is a top or plan view of the same assembly showing the rail joint and portions of the clamp assembly. Similar numbers refer to similar parts of the invention. In Figure 3 is shown a top view of one of the projections extending from the base of the present invention and secured to one of the ties of the track, while Figure 4 depicts the underside of one of the clamps which is mounted over one of the projections shown in Figure 3.

Figure 5 depicts an enlarged cross sectional view, perpendicular to the rail, of a section of the clamp and base shown to the right of the rail in Figure 1, while Figure 6 illustrates a side view of a locking screw which locks the clamp, and also showing the U-shaped locking wedge in place. An enlarged isometric view of the locking wedge is shown in Figure 7.

2

Referring to the drawings, numeral 1 represents a rail laid on ties 2. Under rail 1 is elongated one-piece base 4 extending for some distance under the rail, at least over two to four ties, the center portion being disposed under rail joint 39. This base has arms or projections 5 and 6 which are an integral part of the base. These projections extend over adjacent ties, preferably on both sides of the rail.

Section 4 of base 3 is of the same thickness as the conventional plate now employed under the rails. Projections 5 and 6 of the base act as bases for clamps 7 and 8. Base section 4 is provided with flanges or lips 9, having a thickness of about $\frac{1}{8}$ inch to $\frac{1}{16}$ inch, which are lapped over sides 10 of the base of rail 1, the overlap being about $\frac{3}{8}$ to $\frac{1}{2}$ inch. In this manner, section 4 of the base, together with flanges 9 which have forged overlaps turned toward the rail for substantially the whole length of the base, act as a sleeve for the rail. Projections 5 and 6 extend about 8 inches over the tie from the inner edge of flanges 9.

Clamps 7 and 8, which are about $4\frac{1}{2}$ to 5 inches wide, are attached to projections 5 and 6 of the base, and extend about $\frac{3}{8}$ inch over the edges thereof. These clamps are attached to the projections 5 and 6 by hinges 12 which act as fulcrums for lever sections 13 and 14 and 15 and 16. Both 14 and 15 are somewhat thicker in cross section than 13 and 16. By raising lever sections 13 and 16 which is done by turning screws 17 and 18 upwards, these being about $\frac{1}{2}$ inch in diameter, sections 14 and 15 are forced against rail base sections 10, thereby acting as clamps for the rail. Under lever sections 13 and 16 are seats 19 and 20 for ball bearings 21 and 22 pressed into spherical seats on the tops of screws 17 and 18. When these screws are raised against seats 19 and 20 (which are about $\frac{1}{2}$ inch wide), the ball bearings rotate and relieve any residual torque, thereby allowing screws 17 and 18 to stand considerable vibration without loosening. U-shaped sharp-edged wedges of tempered steel may be forced under the heads of said screws, locking them in place, and thereby making them practically immovable.

Base projections 5 and 6 which are integral parts of the base, all of which sections consist of one piece of steel, are bolted on to tie 2 by bolts 23, 24, 25 and 26, these preferably being $\frac{5}{8}$ inch Allen bolts having a head of about $1\frac{1}{8}$ inch width, although other bolts are suitable. Bolt heads 27 are snugly fit in counterbored portions 29 in base portions 5 and 6. The bolt heads 27 are provided

with recesses 28. Nuts 30 fastened to bolts 23 and 24 are preferably set into recesses cut out in the bottom of tie 2.

Hinge 12, which is about $\frac{1}{2}$ to $\frac{5}{8}$ inch in diameter and preferably made of drill rod material, is driven through reamed hole 32 of housing portion 33 (which is about $\frac{7}{8}$ to 1 inch in outside diameter) of the hinge joint projecting from base portion 5, until it touches the housing end 34 which has hole 35 for enabling the insertion of a driving pin to drive out the pin of hinge 12 and to allow egress of air when said pin is driven in. In the open end 32 of housing 33 is inserted set screws 36 having ball bearing 37 set in its end which seats on the end of hinge 12 at 11. The head of set screw 36 may be in the form of a hexagon, screw head, or other suitable form.

In using the invention, the sleeve is fitted over the end of the rail and slid on to the rail until the portion to be strengthened is reached, as for example a dangerous curve which would generally require a number of such units. When a joint is to be strengthened, the sleeve is fitted over one end of a track, slid on to that track and then slid back to and over the end of the other track making up the joint.

One modification of this invention is the use of a safety device such as that already disclosed, having three flat projections from each side of the base over three ties, the middle projections being centrally disposed over the rail joint to be reinforced. In the reinforcing of rail joints by this means, it is preferable to leave on the conventional sideplates bolted on each side of the rail at the joint, since these serve as additional strengthening members, and also allow the application of the present invention on rails now in existence without the necessity of removing parts thereof.

In the event of a washout caused by floods, a joint reinforced according to the present invention presents a solidarity of construction enabling the whole assembly to remain as a "bridge," an integral unit, allowing a train to pass over, whereas the conventional track construction would involve loosening of the spikes and subsequent derailment of the train. Since the sleeve extends over a substantial portion of the track on each side of the rail joint, this fact together with the pressure of the clamps upon the rail base, make up an assembly of such strength and solidarity as to resist the sinking of the track in an inundated portion.

I claim:

1. A safety device for a track rail laid on ties comprising an elongated metal base disposed under said rail, flanges protruding from said base on each side of the rail and parallel thereto, extending over substantially the whole length of the base, said flanges being turned in toward the base of the rail to allow the rail to rest snugly therein and act as a sleeve therefor, flat projections extending from the side of said base over at least two ties, bolting means for fastening said pro-

jections to said ties, clamps mounted on said projections, and means for tightening said clamps to the upper surface of the base portion of said rail.

5 2. A safety device for a track rail according to claim 1 in which said projections extend from both sides of said base.

3. A safety device for a track rail according to claim 1 in which said projections extend over at least four ties.

10 4. A safety device for a track rail according to claim 3 in which said projections are fastened to the ties by bolts extending through said ties.

5 5. A safety device for a track rail according to claim 4 in which the clamp comprises a lever 15 having a fulcrum substantially in the center thereof, one end of the lever pressing on the top surface of the base portion of said rail, two screws underneath the other end of the lever and threaded into the projection of the base under the rail, 20 said screws capable of being forced up against the lever so as to cause the other end of said lever to grip the rail and hold it tightly against the base under the rail, and ball bearing seats mounted in the heads of said screws at the points of contact with said rail.

25 6. A safety device for a track rail according to claim 5 in which U-shaped, sharp edged wedges are forced under the heads of said screws to lock them in place.

30 7. A safety device for a track laid on ties and having a rail joint, comprising an elongated metal base disposed longitudinally and centrally under said rail joint, flanges protruding from said base on each side of the rail and parallel thereto, extending over substantially the whole length of the base, said flanges being turned in toward the base of the rail to allow said rail to rest snugly therein and act as a sleeve therefor, flat projections extending from both sides of said base over at least

35 four ties, bolting means for fastening said projections to said ties, clamps mounted on said projections, and means for tightening said clamps to the upper surface of the base portion of said rail.

40 8. A safety device for a track rail according to claim 7 in which the bolting means for fastening the projections to the ties comprises bolts which are countersunk in said projections.

45 9. A safety device for a track rail according to claim 8 in which the clamps on the sides of the track are oppositely disposed in relation to each other.

ARNOLD SCHROETTER.
